BY *Frank B. Ade*.
HIS ATTORNEY.

UNITED STATES PATENT OFFICE

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY

VALVE MECHANISM FOR ROCK DRILLS

Application filed January 12, 1929. Serial No. 331,961.

This invention relates to rock drills, but more particularly to a valve mechanism for rock drills of the fluid actuated type.

One object of the invention is to insure an early cut off during the admission of pressure fluid to the cylinder so that the hammer piston may be impelled throughout a portion of its stroke by the expansive force of the pressure fluid.

10 Other objects will be in part obvious and in part pointed out hereinafter.

In the drawings illustrating the invention and in which similar reference characters refer to similar parts,

15 Figure 1 is a sectional elevation of a portion of a rock drill equipped with valve mechanism constructed in accordance with the practice of the invention,

20 Figure 2 is a transverse view taken through Figure 1 on the line 2—2 looking in the direction indicated by the arrows,

Figure 3 is a sectional elevation taken through Figure 2 on the line 3—3 looking in the direction indicated by the arrows, and

25 Figure 4 is a similar view taken through Figure 2 on the line 4—4.

Referring more particularly to the drawings, A represents a cylinder of a rock drill having a piston chamber B in which is disposed a reciprocating hammer piston C. The cylinder A has a free exhaust port D which is controlled by the head E of the piston C. On the forward end of the piston C is a reduced extension F which is guided by a bore G of a front cylinder washer H inserted in the front end of the piston chamber B to form a closure therefor.

In the rearward end of the cylinder A is an enlarged bore J for the reception of a valve chest designated generally by K and rotation mechanism including a rotation ratchet L. The valve chest K in this instance is disposed in the innermost end of the bore J and the rotation ratchet L lies in the rearward end of the bore J. The rotation ratchet L may be of a well known type having the usual inverted teeth O which act as abutments for spring pressed pawls P carried by the head Q of a rifle bar R. The rifle bar R extends 50 rotatably through the valve chest K and is

fluted for engagement with the piston C in a well known manner.

In the illustration shown the rotation ratchet L seats on the valve chest K and in turn serves as a seat for a back head S which forms a closure for the rearward end of the cylinder A.

Among other functions the back head S serves as a housing for a throttle valve T which controls the admission of pressure fluid into the drill. The throttle valve T is of the rotary type and accordingly has a central chamber U which may be in constant communication with a source of pressure fluid through a connection (not shown). In the side of the throttle valve T is a port V intended to afford communication between the chamber U and a passage W in the back head S leading to a supply reservoir X, also in the back head S.

The valve chest K comprises in this instance a pair of plates Y and Z. The plate Z serves as a closure for the rearward end of the piston chamber B and the plate Y is disposed between the plate Z and the rotation ratchet L and the head Q of the rifle bar for which it forms a seat.

The adjacent surfaces of the plates Y and Z are recessed to form a valve chamber b comprising in this instance a reduced portion c and an enlarged portion d. In the plate Y and adjacent the enlarged portion d of the valve chamber is an annular groove e into which pressure fluid may constantly flow from the supply reservoir through supply passages f located in this instance in the rotation ratchet L and the plate Y.

Inlet passages g and h are provided for conveying the pressure fluid from the valve chamber b to the ends of the piston chamber. Both inlet passages g and h lead from the reduced portion c of the valve chamber, the inlet passage g leading to the rearward end of the piston chamber B and the inlet passage h to the forward end of the piston chamber B.

The distribution of pressure fluid to the ends of the piston chamber is controlled by a valve j of the oscillatory plate type having a fulcrum k on its transverse median line whereon the valve j is adapted to rock and on

opposite sides of the fulcrum are wings *o* and *p*. The wing *o* in this instance controls the inlet passage *g*, and the wing *p* controls the inlet passage *h*. Preferably the valve *j* is only of sufficiently smaller size than the reduced portion *c* of the valve chamber *b* so that the valve *j* may have a running fit therein. In other words, the sides of the valve *j* may bear slidably against the adjacent sides of the reduced portion *c* of the valve chamber.

Heretofore in valve structures of the type to which the present invention pertains it has been the practice to rely largely upon the suction of the pressure fluid created on the raised wings of the valve to assist in closing the valve. Other forces of course also act in proper sequence against the valve for tilting it, as for instance, the compression created in the ends of the piston chamber and which compression acts against the valve to assist the suction created by the pressure fluid to throw the valve. In the prior structures, however, the tilting of the valve does not occur until the piston head *E* uncovers the exhaust port to exhaust the pressure fluid utilized for actuating the piston to the atmosphere. This causes a decided drop in pressure forwardly of the valve and enables the forces acting thereagainst to reverse it.

While the prior device operated satisfactorily in most respects it has been found, however, that by delaying movement of the valve until the exhaust port is uncovered a considerable amount of pressure fluid flows directly from the source of supply to the atmosphere without doing any useful work.

The present invention contemplates overcoming this wastage of pressure fluid and to use the pressure fluid expansively for impelling the piston *C*, that is, it contemplates the cutting off of the supply of pressure fluid to the piston chamber before the piston *C* places the active side of the piston chamber *B* in communication with the atmosphere. To this end the plate *Y* is provided with introverted shoulders *q* and *r* which serve in this instance as the ends or bounding surfaces of the reduced portions *c* of the valve chamber. The shoulders *q* and *r* are so spaced with respect to each other that when the adjacent wings of the valve *j* are seated the shoulders will be in substantially slidable engagement with the cooperating surfaces or edges of the valve *j*.

The height of the shoulders *q* and *r* may vary with the requirements of immediate conditions, but it has been found in practice that the most practical height is that in which, when the valve *j* occupies a mean position, that is, when it occupies a position in which it lies perpendicular to the axis of the drill, the edges or ends of the wings *o* and *p* slightly overlie the respective shoulders wherewith they cooperate to cut off communication between the enlarged portion *d* of

the valve chamber *b* and the reduced portion *c*.

In order to assure a maximum flow of pressure fluid over the raised ends or wings of the valve with a minimum lift thereof, the valve *j* is provided in its sides with recesses *s* which preferably extend along the entire side of the valve and may be such height that only a relatively small shoulder or surface *t* remains near the rearward end of the valve for cooperation with the sides of the reduced portion *c* of the valve chamber to cut off communication between the enlarged and reduced portions of the valve chamber.

To the end that a portion of the forward surfaces of the wings *o* and *p* may be exposed to live pressure fluid to accelerate the action of the valve, recesses *u* and *v* are formed in the plate *Z* beneath the wings *o* and *p* respectively, and ports *w* and *x* are formed in these wings for introducing pressure fluid into the recesses when the wings are seated.

The following is a description of the operation of the device: With the valve *j* in the position illustrated in Figure 1, in which the inlet passage *h* is covered by the wing *p* of the valve, pressure fluid will flow over the edge of the wing *o*, thence through the inlet passage *g* into the rearward end of the piston *B* to impel the piston *C* forwardly to deliver its blow against the working implement (not shown). When the head *E* of the piston *C* overruns the exhaust port *D* the air in the front end of the piston chamber *B* will be compressed and will flow through the inlet passage *h* to act against the forward surface of the wing *p* of the valve *j*.

As the piston advances in a forwardly direction the compression pressure will rapidly increase until it reaches a value which, together with the slight suction created on the edge of the wing *o* of the valve, will start the valve to move in the direction of its other limiting position. This occurs just before the head *E* of the piston uncovers the exhaust port *D* and therefore only a short period before the piston delivers its blow. During only a small portion of the movement of the valve *j* will there be any flow of pressure fluid between the edge of the wing *o* and the shoulder *r*. As the valve approaches a position in which it lies substantially perpendicular to the axis of the drill the edge of the wing *o* will move into the plane of the shoulder *r* to cut off the flow of pressure fluid into the rearward end of the piston chamber. While the valve is in this position and during a portion of the subsequent movement of the valve the edge of the wing *p* will also lie in the plane of the cooperating shoulder *q*. During this portion of the movement of the valve there will be no admission of pressure fluid to either end of the piston chamber *B*.

Immediately prior to the delivery of the

blow of the piston against the working implement the compression in the front end of the piston chamber will have reached its maximum pressure and this compression will then act against the wing *p* to rock said wing rearwardly into the enlarged portion *d* of the valve chamber and to move the wing *o* downwardly to seat against the plate *Z*.

In the new position of the valve pressure fluid will flow from the valve chamber *b* over the raised wing *p* and through the inlet passage *h* into the front end of the piston chamber *B* to impel the piston *C* rearwardly. During this movement of the piston and when the exhaust port *D* is covered thereby, the air in the rearward end of the piston chamber *B* will be compressed to act against the forward surface of the wing *o*. The compression thus acting against the wing *o* of the valve, together with the suction created by the pressure fluid flowing over the raised end of the wing *q*, will unseat the wing *o* and will lower the wing *p* into the plane of the shoulder *q* before the wing *o* has been rocked out of the plane of the shoulder *r*. This position of the valve will be assumed before the head *E* of the piston *C* uncovers the exhaust port *D* and the piston *C* will then be actuated rearwardly by the force of the expanding pressure fluid in the front end of the piston chamber to a point where it will uncover the exhaust port *D*. As the piston *C* moves rearwardly the compression in the rearward end of the piston chamber will of course increase in pressure and such compression will then again return the valve *j* to its initial position.

The present invention has been found to be highly advantageous in structures of the type described. Foremost of its advantages are the considerable saving in the matter of pressure fluid consumption due to the early cut off of pressure fluid to the piston chamber, and to the heavy blow which is delivered by the hammer piston to the working implement as a result of this control of the pressure fluid admission.

I claim:

1. In a fluid actuated rock drill, the combination of a cylinder and a piston, an exhaust port in the cylinder controlled by the piston, a valve chamber, inlet passages leading from the valve chamber to the cylinder, an oscillatory plate valve in the valve chamber controlling the inlet passages, and means in the valve chamber cooperating with the valve to cut off the flow of pressure fluid to both ends of the cylinder during a portion of each opening movement of the valve.

2. In a fluid actuated rock drill, the combination of a cylinder and a piston, an exhaust port in the cylinder controlled by the piston, a valve chamber, inlet passages leading from the valve chamber to the cylinder, an oscillatory plate valve in the valve chamber controlling the inlet passages, and means

in the valve chamber cooperating with the valve in an intermediate position of said valve to cut off the flow of pressure fluid to both ends of the cylinder.

3. In a fluid actuated rock drill, the combination of a cylinder and a piston, an exhaust port in the cylinder controlled by the piston, a valve chamber, inlet passages leading from the valve chamber to the cylinder, an oscillatory plate valve in the valve chamber controlling the inlet passages, and means in the valve chamber cooperating with the side of the valve to cut off the flow of pressure fluid to one end of the cylinder prior to the admission of pressure fluid to the other end of the cylinder.

4. In a fluid actuated rock drill, the combination of a cylinder and a piston, an exhaust port in the cylinder controlled by the piston, a valve chamber, inlet passages leading from the valve chamber to the cylinder, and an oscillatory plate valve in the valve chamber to control the inlet passages and cooperating with the bounding surface of the valve chamber to cut off the flow of pressure fluid to one end of the cylinder prior to the admission of pressure fluid to the other end of the cylinder.

5. In a fluid actuated rock drill, the combination of a cylinder and a piston, an exhaust port in the cylinder controlled by the piston, a valve chamber comprising an enlarged portion and a reduced portion, inlet passages leading from the reduced portion to the cylinder, and an oscillatory plate valve in the reduced portion to control the inlet passages and cooperating with the bounding surface of the reduced portion to cut off the flow of pressure fluid to one end of the cylinder prior to the admission of pressure fluid to the other end of the cylinder.

6. In a fluid actuated rock drill, the combination of a cylinder and a piston, an exhaust port in the cylinder controlled by the piston, a valve chamber comprising an enlarged portion and a reduced portion, inlet passages leading from the reduced portion to the cylinder, and an oscillatory plate valve having a pair of wings to control the inlet passages, said wings rocking into the enlarged portion to permit the flow of pressure fluid over the wings into the inlet passages and cooperating with the bounding surface of the reduced portion to cut off the flow of pressure fluid to one inlet passage prior to the admission of pressure fluid to another inlet passage.

7. In a fluid actuated rock drill, the combination of a cylinder and a piston, an exhaust port in the cylinder controlled by the piston, a valve chamber having a shoulder to form a reduced portion in the valve chamber, inlet passages leading from the reduced portion to the cylinder, and an oscillatory plate valve in the reduced portion controlling the

inlet passages and cooperating with the shoulder in an intermediate position of the valve to cut off the flow of pressure fluid to one end of the cylinder prior to the admission of pressure fluid to the other end of the cylinder.

8. In a fluid actuated rock drill, the combination of a cylinder and a piston, an exhaust port in the cylinder controlled by the piston, a valve chamber having a shoulder to form a reduced portion in the valve chamber, inlet passages leading from the reduced portion to the cylinder, an oscillatory plate valve in the reduced portion controlling the inlet passages and cooperating with the shoulder in an intermediate position of the valve to cut off the flow of pressure fluid to one end of the cylinder before the admission of pressure fluid to the other end of the cylinder, and recesses in the sides of the valve to insure a maximum admission of pressure fluid into the cylinder with a minimum lift of the valve.
9. In a fluid actuated rock drill, the combination of a cylinder and a piston therein, an exhaust port in the cylinder controlled by the piston, a valve chamber having shoulders on opposite sides thereof to form a reduced portion in the valve chamber, inlet passages leading from the reduced portion to the cylinder, an oscillatory plate valve in the reduced portion having wings to control the inlet passages and cooperating with the shoulders to effect the cut-off of pressure fluid to one end of the cylinder before establishing communication between the valve chamber and the other end of the cylinder, thereby enabling the piston to be actuated throughout a portion of its stroke by the expansive action of the pressure fluid.

In testimony whereof I have signed this specification.
